FRANK T. JONES, OF BALTIMORE, MARYLAND, ASSIGNOR TO THE JONES SAFETY TRAIN CONTROL SYSTEM COMPANY, OF BALTIMORE, MARYLAND, A CORPORATION OF MARYLAND.

SAFETY AIR-BRAKE VALVE.

2,044,306.

Specification of Letters Patent.

Patented Dec. 31, 1912.

Application filed January 12, 1912. Serial No. 670,792.

To all whom it may concern:

Be it known that I, FRANK T. JONES, a citizen of the United States, residing at Baltimore, in the State of Maryland, have invented certain new and useful Improvements in Safety Air-Brake Valves, of which the following is a specification.

This invention relates to an electro-pneumatic safety train-controlling valve for air brakes, and has particular reference to a valve of this character to be used in an electric train-controlling mechanism on railroads.

The invention is particularly applicable for use in a safety system like, or somewhat similar to that set forth in U. S. Patent No. 1,010,371 granted on November 28th, 1911 to me and Richard T. Jones jointly, wherein in the roadway is provided at intervals with short ramp or contact rails, having a connection with a local current supply so that a shoe on the vehicle during its passage over said ramp rail may, in cases of safety conditions ahead, pick up a current from the ramp rail and throw it into circuit with mechanism on the vehicle to prevent the operation of the air-brakes, and in case of danger conditions ahead to cut off the connection between the ramp rail and the said local current supply, to prevent said current from passing to the vehicle, thus causing the brakes to be applied.

The present invention relates particularly to the air-brake controlling mechanism and the circuits on the vehicle to control the same.

The accompanying drawing illustrates the invention in which,

Figure 1, diagrammatically illustrates a portion of the track rail; the ramp rail and local current supply and the devices and circuit on the vehicle. Fig. 2, shows a sectional elevation of the controlling-valve mechanism, and Fig. 3, a sectional plan view on the line 3-3 of Fig. 2.

Referring to the drawing the numeral, 1, designates a case having two doors, 2, and 3, respectively, each preferably having glass plates whereby parts therein may be viewed through the glass. This case may be located at any convenient place in the cab of the locomotive, motor or other vehicle but is preferably conveniently accessible to the engineer.

It is desirable that each door be provided

with a suitable indicator device, 4, in addition to a lock,—the key hole, 5, to which is shown, so that in case a door is opened, the fact of such opening will be indicated and the engineer be required to account for such opening.

A pipe, 6, enters the case from the train line and is provided with a valve, 7, on the inside of the case in order that by opening the door, 2, access may be gained to the valve so as to entirely cut-off the train line connection. This may be necessary in case one engine or motor is acting as a helper to another under which conditions the valve device on the helper will be cut out. A branch pipe, 8, extends laterally from the train line pipe, 6, above the valve, 7, and said branch pipe enters a vertical pipe, 9, which extends upwardly in the case to a point at one side of the upper door, 3. This vertical pipe, 9, is provided with a valve, 10, at its lower end and at its upper end has a valve, 11. By reference to Fig. 2, it will be noted that the valves, 10, and, 11, in the stand or vertical pipe, 9, have positions adjacent to the doors, 2, and, 3, and by reference to Fig. 3, it will be seen that valve, 10, has a stem, 12, which projects through the casing wall, 13, and is exposed on the outer side of the case. The same is true of the stem, 14, of valve, 11. The outer ends of these valve stems, 12, and, 14, are provided with arms or handles, 15, and, 16, respectively, and it will be noted that these arms or handles project over the edges of the doors, 2, and, 3. The valves are in the cut-off position and positions of the handles are such that before either door can be swung open the handle that projects over such door must be turned, but in doing so the valve will be opened and the air from the pipes, 9, 8, and, 6, will escape, thus causing a reduction of train pipe pressure and an application of the brakes.

Above or beyond the branch pipe, 8, there is provided another valve, 17, and a short section of pipe, 18, extends from said valve and enters a port, 19, in one end of a cylinder, 20. This cylinder has a valve seat, 21, at the inner side of the port, 19, and is also provided with a plurality of circumferential air ports, 22, beyond the said valve seat. A piston head, 23, snugly fits the interior of the cylinder and one end of said head is provided with a valve, 24, which in the present

instance is of a cone-shape to correspond with the shape of the seat, 21, at the inner end of port, 19. The opposite end of the cylinder is closed, in the present instance, by 5 means of a screw-threaded plug, 37, into the outer end of which a short section of pipe, 25, is fitted. A pipe, 26, enters the case, 1, preferably from the main air reservoir on the locomotive, motor or vehicle, which latter is not shown because it is a well known 10 adjunct to the ordinary air-brake equipment, and an electro-pneumatic valve device, 27, is interposed between said reservoir pipe, 26, and the cylinder pipe, 25. In the present instance this electro-pneumatic valve device, 15 27, comprises an elbow-shaped casing having a port, 28, which provides communication between the main reservoir pressure in pipe, 26, and the cylinder, 20, and another port, 29, to the atmosphere, or to the interior of the case, 1, which latter has perforations, 30, in its walls. An electro-magnet, 31, is suitably mounted in the case, 1, and adjacent to the atmosphere port, 29, of the pneumatic 20 valve device, 27, so that an armature, 32, may be attracted by the magnet and carry a valve stem, 33, on which two valves, 34, and, 35, respectively are mounted.

The valve, 34, is carried on the upper end 30 of the stem and has position above the port, 28, while valve, 35, is mounted on the stem below the port, 29. The relative position of these valves is such that normally, when the magnet is energized and the armature, 32, 35 and valve stem, 33, held in an elevated position, the lower valve, 35, will close port, 29, while the upper valve, 34, will be lifted from the port, 28, to allow reservoir air to pass to the cylinder, 20. This position of 40 the valves is the normal running condition with the brakes held off, but of course the latter may be operated by manipulations of the engineer's valve for all the usual service and emergency applications.

45 A spring, 36, is compressed in the cylinder, 20, between the plug, 37, and piston head, 23, so as to exert a pressure on top of the said head and aid in seating the valve, 24, against the train line pressure.

50 From the foregoing explanation it is obvious that if the electro-magnet, 31, becomes deenergized, the valve stem, 33, and valves, 34, and, 35, will drop,—the valve, 34, thereby closing the port, 28, and shutting off the 55 main reservoir air and the valve, 35, opening port, 29, to the atmosphere thus allowing the air to escape from the upper side of the piston head, 23, in cylinder, 20. This escape of air on the upper side of piston, 23, removes 60 the air pressure from that side of the head while the pressure in the train line will act on the underside of the head and raise the latter in said cylinder which causes valve, 24, to uncover port, 21, and allow train line 65 air to vent to the atmosphere through ports,

22, in the cylinder. This reduction of train line pressure will effect an application of the brakes in the same manner as though the engineer had brought it about by manipulating his engineer's valve.

It only remains therefore to set forth the 70 automatic electric circuits by which the electro-magnet, 31, is energized and the means for interrupting those circuits to cause an application of the brakes when desired.

By reference to Fig. 1, wherein the vehicle is diagrammatically shown, it will be seen that the track rail, 38, has a connection, 39, that extends to a suitable contact plate, 40, 80 and that an armature, 41, is mounted so as to be held, under certain conditions, against said plate, 40. An electro-magnet, 42, is also provided which latter is kept energized by a circuit that includes line wire, 43, only when the track ahead is clear as fully explained in 85 said U. S. Patent 1,010,371 hereinbefore referred to. A connection, 44, extends from the armature, 41, to one pole of a battery, 45, or other source of current.

Ramp rails, 46, are also provided at intervals along the trackway and each ramp rail is provided with a conductor that connects it with the other pole of the battery, 45. It will thus be seen that as long as 95 line wire, 43, conducts current through electro-magnet, 42, the latter will remain energized and hold the armature, 41, in the attracted position where it will connect track-rail, 38, and ramp rail, 46, with battery, 45, but the circuit from the said battery, 45, through track and ramp rails, 38, and, 46, is never completed until the vehicle arrives at the ramp rail and is then only completed through the vehicle in case 100 the track ahead is clear and magnet, 42, is energized. The vehicle is provided with a contact shoe of any suitable construction but in the present instance is shown as two depending arms, 47, and, 48, respectively 110 insulated from each other. These arms normally engage suitable contact plates, 49, and, 50, and a conductor, 51, extends from arm, 47, and connects with the electro-magnet, 31, in the case, 1, on the vehicle which 115 magnet controls the stem, 33, and valves, 34, and, 35. A conductor, 52, then extends from said electro-magnet, 31, to the axle, 53, of the vehicle and from the axle connection is made with track rail, 38, by means 120 of the wheel, 54.

A battery, 55, or other current supply is provided on the vehicle and one conductor, 56, extends from one pole of said battery to and connects with contact plate, 49, while 125 another conductor, 57, extends from the other pole of said battery, 55, to and connects with contact plate, 50.

It will thus be understood that normally 130 and when the shoe arms are in the position

shown in Fig. 1, which is at all times when the vehicle is traveling between two ramp rails, 46, a circuit will be maintained on the vehicle from battery, 55, conductor, 56, 5 contact plate, 49, arm, 47, and conductor, 51, to electro-magnet, 31, to energize that magnet while the vehicle is between ramp rails, then returning from said magnet the circuit will be by conductor, 52, to axle, 53; conductor, 58, to arm, 48, of the shoe, then to contact plate, 50, and by conductor, 57, back to the other pole of the battery, 55. This normal vehicle circuit will keep the electro-magnet, 31, energized and as long 10 as said magnet is energized the armature, 32, will keep valve stem, 33, raised so that inlet port, 28, will be open and escape port, 29, will be closed by valves, 34, and, 35, respectively consequently air pressure of the 15 main reservoir will be maintained on top of piston-head, 23, in cylinder, 20, and being greater by fifteen or twenty pounds than the pressure from the train line, 6, at the bottom of valve, 24, will keep said latter 20 valve seated on the port, 21, and thus prevent the train line air from escaping into the cylinder, 20. By thus maintaining the train line pressure the air-brakes will be held off or in the released position in the 25 usual manner.

When the vehicle reaches a ramp rail, 46, the arm, 49, of the contact shoe will ride up the end of said ramp rail and in doing so will break the connection between contact plates, 49, and, 50, and shoe arms, 47, and 48, thus interrupting the normal vehicle circuit from battery, 55, to electro-magnet, 31, and return. Obviously, unless current from some source other than from 30 battery, 55, be substituted at the moment when the said normal circuit is interrupted as just above described, the electro-magnet, 31, on the vehicle will be deenergized and would cause an emergency application of 35 the brakes as will presently be explained, but if the track ahead is clear the application of the brakes must be and is avoided as follows—As the shoe arm, 49, passes onto ramp rail, 46, it will pick up or continue the circuit from ramp rail battery, 45, through the arm, 47, to electro-magnet, 31, and at the same time this circuit will be completed from said magnet, 31, by returning by way of conductor, 52, to axle, 53, wheel, 54, rail, 38, conductor, 39, contact plate, 40, armature, 41, and conductor, 44, back to the said ramp rail battery, 45. By thus temporarily substituting the current 50 from battery, 45, through magnet, 31 in place of the current from vehicle battery, 55, which has been interrupted, the said electro-magnet, 31, will be maintained in an energized condition and the brakes will be kept in the release condition, because the track 55 ahead is clear.

Now presuming the track ahead to be occupied or the rails broken. Such a condition would interrupt the current that would otherwise pass through track magnet, 42, by line wires, 43, and this latter magnet 70 would become deenergized and allow armature, 41, to drop from contact plate, 40. This would break the connection from ramp rail battery, 45, to track rail, 38, and consequently a circuit could not be completed 75 from said latter battery when the shoe arm, 47, passed onto ramp rail. Obviously a deenergization of electro-magnet, 31, would result because of the lack of current, and stem, 33, would drop and allow valve, 34, to 80 close so reservoir pressure would be cut off from the pipe, 25, and cylinder, 20, and at the same time valve, 35, would drop and uncover port, 29, thus allowing the air to escape from pipe, 25, and cylinder, 20. The 85 release of the pressure on the upper side of piston head, 23, would immediately allow the greater train-line pressure on the under side of the piston head to raise valve, 24, and said piston head. This movement would 90 permit the train line air to escape into cylinder, 20, and then out by ports, 22, so as to materially reduce the pressure in the train line and by this reduction an application of the brakes would be automatically effected 95 in the usual and well known manner.

By providing a case and inclosing the controlling mechanism therein so that access cannot be gained thereto except by means of the doors and then only upon registering each 100 time a door has been opened, interference with the apparatus on the part of the engineer will be reduced to a minimum because the doors cannot be opened without first venting the train line of pressure by the turning of one or the other of valve handles, 15, or, 16.

Having thus described my invention what I claim and desire to secure by Letters Patent is—

1. In an air-brake valve device for vehicles which latter travel on tracks, the combination with a vehicle having an air-brake system, of a train-line connection with the air-brake system; a connection from the main reservoir of the said air-brake system; means for normally holding the train-line connection closed by pressure from the reservoir; means for controlling the reservoir pressure to the closing means of the train-line; and a circuit on the vehicle including the said means that controls the air-reservoir pressure.

2. In an air-brake valve device for vehicles which latter travel on tracks, the combination with a vehicle having an air-brake system, of a train-line connection with the air-brake system; a connection from the main reservoir of the said air-brake system; means for normally holding the train-line

connection closed by pressure from the reservoir; valve means for controlling the reservoir pressure to the said closing means of the train line; an electro-magnet to control 5 said valve means; and a circuit on the vehicle which includes the said electro-magnet.

3. In an air-brake valve device for vehicles which latter travel on tracks, the combination with a vehicle having an air-brake system, of a cylinder on the vehicle having a movable piston-head; a connection between one side of the head in said cylinder and the train-line pressure of the air-brake system; means for normally retaining said head to prevent escape of air from the train line, said means being controlled by an electro-magnet; and a normal circuit including the said electro-magnet to keep the latter 20 energized.

4. In an air-brake valve device for vehicles which travel on tracks, the combination with a vehicle having an air-brake system of a cylinder on the vehicle having a movable piston head therein; an air-brake train line connection with the cylinder and at one side of the piston head; an air-brake reservoir connection with the cylinder and at the other side of the piston head to normally 25 hold the said piston head to prevent the escape of air from the train line; a valve in the reservoir connection; a movable device on the vehicle; and means coacting between the said movable device and the valve in the 30 reservoir connection to control the said valve.

5. In an air-brake valve device for vehicles which travel on tracks, the combination with a vehicle having an air-brake system of a cylinder on the vehicle having a movable piston head therein; an air-brake train line connection with the cylinder and at one side of the piston head; an air-brake reservoir connection with the cylinder and at the other side of the piston head to normally 40 hold the said piston head to prevent the escape of air from the train line; a valve in the reservoir connection; a movable device on the vehicle; an electro-magnet to control the said valve, and a circuit normally 45 on the vehicle including a source of current supply, the said movable device and the electro-magnet.

6. In an air-brake valve device for vehicles which travel on tracks, the combination with a vehicle having an air-brake system of a cylinder on the vehicle having a movable piston head therein; an air-brake train line connection with the cylinder and at one side of the piston head; an air-brake 55 reservoir connection with the cylinder and at the other side of the piston head to normally hold the said piston head to prevent escape of air from the train line; a pressure controlling device in said reservoir connection having a port for the passage of reser-

voir air to one side of said piston head and another port for the escape of air from said side of the piston head; a valve for each of said ports; an electro-magnet to control said valves and to hold one open and the other seated; a movable device on the vehicle, and a circuit normally on the vehicle and including the said movable device and electro-magnet.

7. In an air-brake valve device for vehicles which travel on tracks, the combination with a vehicle having an air-brake system of a cylinder on the vehicle having a movable piston head therein; an air-brake train line connection with the cylinder and at one side of the piston head; an air-brake reservoir connection with the cylinder and at the other side of the piston head to normally hold the said piston head to prevent escape of air from the train line; a pressure controlling device in the reservoir connection said device having two ports one of which controls the passage of reservoir air to the piston head and the other controls the escape of air to the atmosphere; an electro-magnet; an armature; a stem; two valves on the stem one for each of said ports; and a circuit normally maintained on the vehicle to energize said electro-magnet and normally hold one of said valves unseated and the other seated.

8. In an air-brake valve device for vehicles which latter travel on tracks, the combination with a vehicle having an air-brake system, of a cylinder having piston head therein and also having a train-line connection at one side of the head; a reservoir connection at the other side of the head with ports leading to the atmosphere; a pressure controlling device in the reservoir connection said device having valve means for admitting reservoir pressure to one side of the said piston head or releasing pressure from said side of the head; an electro-magnet for holding the valve means normally in a position to allow the reservoir pressure to act on the piston head; a movable device on the vehicle, and a circuit normally including the movable device and electro-magnet.

9. In an air-brake valve device for vehicles which latter travel on tracks, the combination with a vehicle having an air-brake system, of a cylinder having two spaced-apart ports and also having ports that open to the atmosphere between the two spaced-apart ports; a piston head in said cylinder between the two spaced-apart ports, said head having a valve at one side to normally close one of the two spaced-apart ports; a train-line pipe connection with the normally closed port of said cylinder; a reservoir-air pipe connection with the other of said two spaced-apart ports; a valve in said latter pipe; an electro-magnet for controlling said

- valve; a movable device on the vehicle and a circuit including the movable device and magnet for normally energizing the latter to hold the valve so that reservoir air will seat the valve on the piston head over the port that delivers the train-line air to the cylinder.
10. In an air-brake valve device for vehicles which latter travel on tracks, the combination with a vehicle having an air-brake system, of a case on the vehicle; a connection from the train-line of the air-brake system entering the said case; a connection from the air-reservoir of the air-brake system also entering the case; means in the case for normally holding the train-line connection in the case closed by the pressure from the air reservoir connection; means also in the case for controlling the air-reservoir pressure; a movable device on the vehicle and a circuit also on the vehicle including the movable device and the said means in the case that controls the air-reservoir pressure.
15. 11. In an air-brake valve device for vehicles which latter travel on tracks, the combination with a vehicle having an air-brake system, of a case on the vehicle; means in the case for controlling the escape of air from the train-line of the air-brake system by pressure from the air-reservoir of the said air-brake system; a movable device on the vehicle and means actuated through the movement of the said movable device 30 to cut-off the pressure from the said air reservoir to allow the train-line pressure to escape.
20. 12. In an air-brake valve device for vehicles which latter travel on tracks, the combination with a vehicle having an air-brake system, of a case on the vehicle; means in the case for controlling the escape of air from the train-line of the air-brake system by pressure from the air reservoir of the 35 said air-brake system; a door to the said case; a movable device on the vehicle; means actuated by the movement of the
- movable device to cut-off the said reservoir pressure and vent the train-line, and means for controlling the train-line pressure and 50 coacting with the door of the case to prevent opening of the door except by venting the train line.
13. In an air-brake valve device for vehicles which latter travel on tracks, the combination with a vehicle having an air-brake system, of a case on the vehicle; a door to the case; means in the case for controlling the escape of air from the train-line by pressure from the air-reservoir of the said 55 air-brake system; valve means to control the air-reservoir pressure to the said train-line controlling means; an electro-magnet to hold the valve means so that pressure from the air-reservoir can pass; a movable device 60 on the vehicle; a circuit on the vehicle including the movable device and electro-magnet and means for also controlling the train-line pressure and coacting with the door of the case to require venting of the 65 train-line before opening of the door.
14. In an air-brake valve device for vehicles which latter travel on tracks, the combination with a vehicle having an air-brake system, of a case on the vehicle; a movable 70 door for the case; indicating means actuated by the movement of the door; means in the case for controlling the escape of air from the train line of the brake system by pressure from the air reservoir of said system; a movable device on the vehicle; means actuated by the movement of the movable device to cut off the said reservoir pressure and vent the train line and means also controlling train line pressure and coacting 75 with the door of said case to prevent opening the door except by first venting the train line.

In testimony whereof I affix my signature in presence of two witnesses.

FRANK T. JONES.
